PLUMBING FIXTURE PROTECTOR

Donald D. Wagner, El Monte, Calif.

Application October 9, 1953, Serial No. 385,147

5 Claims. (Cl. 150—52)

This invention has to do with a plumbing fixture protector and it is a general object of the invention to provide a simple, practical protector applicable to a plumbing fixture, or the like, and adapted to protect the fixture from general abuse and falling objects.

In the construction of houses or buildings different contractors are employed to carry out separate operations or jobs, such as carpentry, electrical wiring, heating, plastering, tiling and plumbing. In the ordinary sequence of operations, the plumber is obligated to, and must, install certain fixtures, such as porcelain sinks, trays, water closets and tubs, before the other phases or operations are started. Consequently, it is not uncommon for the various tradesmen to mis-use the above mentioned fixtures and to accidentally mar or deface them in the course of their operations. For example, a bathtub is especially vulnerable and is very often damage so extensively that it is even necessary to replace the tub. In view of this situation I will in this disclosure refer specifically to a form of the present invention for use over a bathtub, and will describe the present invention as related to such a situation.

It is an object of the invention to provide a protector of the general character referred to, which is of simple, inexpensive construction and which is such that it can be easily and conveniently applied to a fixture, such as a tub, without the exercise of any great skill.

Another object of the invention is to provide a protector of the general character referred to, which is of plain, simple construction and is such that it can be conveniently and easily cleaned and re-used.

It is a further object of this invention to provide a protector of the character referred to, which may be left in place when the fixture to be protected is installed while the other necessary building operations are carried on.

The various objects and features of my invention will be fully understood from the following detailed description of a typical preferred form and application of my invention, throughout which description reference is made to the accompanying drawings, in which:

Fig. 1 is a perspective view of a corner of a room, such as a bathroom, showing the protector applied to a tub. Fig. 2 is an enlarged detailed sectional view taken as indicated by line 2—2 on Fig. 1. Fig. 3 is an enlarged detailed sectional view taken as indicated by line 3—3 on Fig. 1. Fig. 4 is a perspective view showing the protector removed from the tub. Fig. 5 is an enlarged detailed view showing a portion of the structure with a part folded away from and clearing the wall of the building, and Fig. 6 is an enlarged sectional view showing the retaining means that I have provided.

As shown throughout the drawings, the building or structure to which the plumbing fixture protector is applicable involves, generally, walls W, a floor F, and a plumbing fixture or tub T. The walls W, as shown, include the framing or wood structure, the plastering and the tiling. In practice, the wood framing is ordinarily erected prior to installation of the tub and the plastering

2

and tiling are installed after the tub is in place. Also, other operations, such as plumbing, heating, electrical wiring and painting, are all carried out after the tub is installed.

5 The protector provided by the present invention involves, generally, a top panel A which includes stiffening means and flaps, a front panel B which includes stiffening means and flaps, one or two end panels C, when desired, which includes stiffening means and flaps, and retainers or stops D for holding the protector in place on the fixture. In the preferred form of the invention the top A and front B are integrally formed of heavy flexible material, such as canvas or the like. The end panel C is shown detachable from the other two elements and is 10 also formed of heavy flexible material, or the like. When I refer to heavy flexible material or canvas, I mean to include any pliable sheet material or the equivalent thereof, such as belting, fiber-glass or plastic. However, since I prefer to use heavy fiber-glass sheet I will describe my 15 invention as being made thereof.

The top A is horizontally disposed and involves a body or panel 10 of heavy flexible sheet, stiffening means 11, and flaps 17, 18 and 19. The top panel 10 overlies the tub T and corresponds in size and shape with the tub. 20 The panel 10 is a simple, rectangular, elongate element having parallel side edges 13 and 14, and parallel end edges 15 and 16, and the flaps 17, 18 and 19 occur at the margins or edges of the top A. The flaps 17, 18 and 19 are preferably formed integral with the body or panel 25 10 of the top, and flap 17 is a side flap which is coextensive with the side edge 13 of the panel 10. Flap 17 is adapted to be turned up and back, or under, as shown in Fig. 5 of the drawings. The flaps 18 and 19 are end flaps which are coextensive with the end edges 15 and 30 16, respectively, and may be turned up and back, or under, in the same manner as the flap 17.

The stiffening means 11 involves simple, elongate battens 20 which extend across or transversely of the top A. There is a plurality of battens 20 located beneath 35 the panel 10, and each batten is preferably a simple, flat board of lumber, or the like, with parallel sides 21 and ends 22 normal thereto. As shown, the battens are located under the top A and terminate at points spaced from the edges 13 and 14, so that the flap 17 is free to be folded, as shown in Fig. 5 of the drawings.

The battens 20 may be secured to the top A in various manners. However, I choose to enclose them in suitable pockets 23. Each pocket 23 is formed by providing an element 24 of heavy flexible sheet, or the like, sewed to the underside of the panel 10. Parallel lines of stitching 25 are spaced apart to occur at the sides of the element 24 so that a batten 20 is readily insertable into the pocket. The ends of the pocket 23 are closed off by lines of stitching 26 after the batten 20 is in place.

The front B is vertically disposed when in place and involves a body or panel 30 of heavy flexible sheet, or the like, and is preferably integral with the panel 10 of the top A. The front involves stiffening means 31 and flaps 37, 38, and 39. The panel 30 is a simple, rectangular, elongate element having parallel upper and lower edges 33 and 34, and parallel vertical end edges 35 and 36. The panel 30 overlies, or overhangs, the front of the tub T and is bordered by the marginal flaps 37, 38 and 39. The upper edge 33 is coextensive with and joins the side edge 14 of the top A where the material forming the top A and front B is folded, so that the front B depends downwardly from the edge 14 of the top.

70 The flap 37 is a bottom flap and is coextensive with the edge 34 of the front B. The flap 37 may be turned up or under in the same manner as described in connec-

tion with the flap 17 above described. The flaps 33 and 39 are end flaps which are coextensive with the vertical edges 35 and 36, respectively, and may also be turned up or under as above described.

The stiffening means 31 involves simple, flat, elongate battens 40 which extend across or vertically of the front B. There is a plurality of battens 40 located beneath or at the inside of the panel 30, and each batten is preferably a simple, flat board of lumber, or the like, having parallel sides 41 and ends 42 normal thereto. As shown throughout the drawings, the battens are located under the panel 30 and terminate at points spaced from the edges 33 and 34, so that the flap 37 is free to be folded.

It is to be noted that by terminating the battens 20 at a point spaced from the edge 14, and the battens 40 at a point spaced from the edge 33, the panels 10 and 30, which are integral, are easily folded relative to each other. The flaps 18 and 19 and the flaps 33 and 39 have free ends 18^a and 19^a, and 33^a and 39^a, respectively, so that the flaps are movable independently of each other. These ends are formed by cutting a simple slit in the canvas between adjacent ends of the flaps.

The battens 40 may be secured to the panel 30 of the front B in the same manner as the battens 20 are secured to the panel 10 of front A. As shown in the drawings, the battens 40 are enclosed in pockets 43 formed by an element of flexible sheet material sewed to the underside of the panel 30. Parallel lines of stitching 45 are spaced apart so that the batten 40 is readily insertable into the pocket. The ends of the pocket 43 are closed off by lines of stitching 46 after the batten 40 is in place.

The ends C are vertically disposed when in place and involve a body or panel 50 of heavy flexible sheet, or the like, and are preferably removable from the top A. It is to be understood, however, that each end C may be integral with the top, like the front B, or may be sewed thereto, as desired. The ends C are shown releasably fastened to the panel A and each end C includes stiffening means 51, and extension 57, and flaps 58, 59 and 60. The panel 50 is a simple, rectangular element having parallel upper and lower edges 53 and 54, and parallel vertical edges 55 and 56. The extension 57 is coextensive with and projects from the upper edge 53 and is preferably integral therewith.

As shown in the drawings, the end portions of the top A or flaps 18 and 19 are provided with suitably spaced fasteners 70, and registering fastening elements 71, which are adapted to snap onto the fasteners 70, are provided on the extension 57. The flaps 59 and 60 are side flaps and are coextensive with the edges 53 and 56, and the flap 58 is a bottom flap and is coextensive with the edge 54. The flaps 58, 59 and 60 are all foldable in the manner above described and as shown in Fig. 5 of the drawings.

The stiffening means 51 involves simple, flat, elongate battens 65 which extend across or vertically of the end C. A plurality of battens is preferably provided and each involves a simple, flat board of lumber, or the like, having parallel sides 66 and ends 67 normal thereto. As shown in the drawings, the battens are located under the panel 50, or at the inside thereof, and terminate at points spaced from the edges 53 and 54, so that the flap 60 and the extension 57 are free to be folded as above described.

It is a feature of the fixture cover which I have provided that the battens 20, 40 and 65 not only act to stiffen the panels A, B and C but, in addition, act to space the panels away from the surfaces of the fixture. The battens are all located or placed at the insides of the panels, that is, the sides of the panels which face the fixture. Thus, the top panel A is supported from underneath by the battens 20.

The pockets, formed of the sheet material, which house the battens 20, 40 and 65 present relatively soft

surfaces for engagement with the fixture, so that there is little or no tendency to mar the finish of the fixture where the battens engage the fixture. It will be clear from Fig. 2 of the drawings how the ends of the battens 20 support the top panel A.

The retainers or stops D which hold the top A in place involve lugs or projections 80 which depend from the battens 20. As shown in Fig. 2 of the drawings, there is a projection at the end of each batten near the edge 14 suitably spaced from the edge so that the projection engages the inside of the tub T. It will be readily understood how this simple means prevents the protector as a whole from sliding forward, and it will be equally clear how the edge 13 of the heavy stiff sheet material prevents movement in the opposite direction. In the preferred form of the invention the projections 80 are in the form of rubber bumpers secured to the battens 20 by means of screws 82.

From the foregoing detailed description of the fixture cover that I have provided, it will be apparent how the cover is applied to a bathtub which has been installed in a building structure. It will also be apparent how the flaps that I have provided may be individually folded away from the wall, or floor, as the case may be, in order to clear the same. It is to be noted that once the protector is installed it may be manipulated without being removed from the tub, so that any all work may be performed by the other tradesmen. When the protector is not in use it may be folded or rolled up as desired.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A protector of the character described, applicable to a fixture having an open horizontally disposed flat top and a vertically disposed front, including, a top panel coextensive with and covering the top, battens extending across the top to have supporting engagement with the side parts of the fixture and reinforcing the top, and a front panel coextensive with and covering the front.

2. A protector of the character described, applicable to a fixture having an open horizontally disposed flat top and a vertically disposed front, including, a top panel coextensive with and covering the top, battens extending across the top to have supporting engagement with the side parts of the fixture and reinforcing the top, a front panel coextensive with and covering the front, and projections depending from the top and engageable with the fixture to retain the protector on the fixture.

3. A protector of the character described, applicable to a fixture having a horizontally disposed top and a vertically disposed front, including, a top panel coextensive with and covering the top, battens extending across and reinforcing the top, flaps along the margins of the top, a front panel depending from the top coextensive with and covering the front, battens extending across and reinforcing the front, and flaps along the margins of the front.

4. A protector of the character described, applicable to a fixture having a horizontally disposed top, a vertically disposed front, and a vertically disposed end, including, a top panel coextensive with and covering the top, battens extending across and reinforcing the top, flaps along the margins of the top, a front panel depending from the top coextensive with and covering the front, battens extending across and reinforcing the front, flaps along the margins of the front, an end panel depending from the top coextensive with and covering the end, battens extending across and reinforcing the end, and flaps along the margins of the end.

5. A protector of the character described, applicable to a fixture having a horizontally disposed top, a verti-

cally disposed front, and a vertically disposed end, including, a top panel coextensive with and covering the top, battens extending across and reinforcing the top, flaps along the margins of the top, a front panel depending from the top coextensive with and covering the front, battens extending across and reinforcing the front, flaps along the margins of the front, an end panel depending from the top coextensive with and covering the end, battens extending across and reinforcing the end, flaps along the margins of the end, and projections depending from the top, and engageable with the fixture to retain the protector on the fixture.
